UNITED STATES PATENT OFFICE.

FRANCIS M. LECHNER, OF WAYNESBURG, ASSIGNOR TO THE LECHNER MINING MACHINE COMPANY, OF COLUMBUS, OHIO.

MINING-MACHINE.

SPECIFICATION forming part of Letters Patent No. 239,515, dated March 29, 1881.

Application filed November 19, 1880. (No model.)

To all whom it may concern:

Be it known that I, FRANCIS M. LECHNER, a citizen of the United States, residing at Waynesburg, in the county of Stark and State of Ohio, have invented certain new and useful Improvements in Mining-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 is a top-plan view of a mining-machine embodying my improvements, with the exception of the cleaner-chains and their operating mechanism, they being detached in this figure to more clearly show other parts. 20 Fig. 2 is a central vertical section of the devices shown in Fig. 1, taken on line *x x* of Fig. 1. Fig. 3 is a transverse section of the same devices, taken on line *y y* of Fig. 1, showing, also, the rear brackets and pulleys of the cleaner-chains. Fig. 4 is a front elevation of the rear sliding standard and the detachable nut carried thereby. Fig. 5 is a side elevation of the devices shown in Fig. 4. Fig. 6 is a top-plan view of the front portion of the mining-machine, showing the method of attaching and operating the cleaner-chains, the engine and the motor parts of the machine being removed. Fig. 7 is a transverse section of the machine with a modification of the withdrawing mechanism. Fig. 8 is a side elevation of part of the devices shown in Fig. 7. Fig. 9 is a view of an octagon sprocket adapted for use upon the chain-driving shaft.

40 The invention relates to an improved arrangement of the operative parts of the mining-machine relative to the supporting-frame, whereby the engine may be made stationary, and the sliding carriage which supports the cutting apparatus may be relieved of the weight of the engine.

The invention relates, also, to an improved arrangement of the parts of a mining-machine, whereby it requires or occupies a space much less than that heretofore required.

45 It relates, further, to the combination, with

the engine and cutting mechanism (the latter arranged both to reciprocate and also to rotate) of a screw-shaft constructed and arranged to convey the power which reciprocates the cutting mechanism, and also the power which rotates said mechanism.

It relates, also, to the combination, with an engine and a sliding cutter-carriage, of a screw-threaded shaft, and mechanism arranged to engage with said shaft for the purpose of withdrawing the cutter-carriage after the cutting has been completed.

It relates to an improvement in the devices for withdrawing the "slack" or cuttings.

It consists in various improvements in details of construction and arrangement which will be hereinafter fully set forth.

The parts not hereinafter set forth may be similar to those shown in any of the various patents issued to me heretofore, to wit: Nos. 70 173,637, January 25, 1876; 186,856, January 30, 1877; 197,734, December 4, 1877; 211,100, January 7, 1879; 223,626, January 13, 1880; and 232,280, September 14, 1880.

In the constructions shown in these last said 75 patents, use was made of engines having cylinders whose longitudinal axes were situated on vertical lines, and which engines, also, were attached to and carried by the sliding cutter-carriage. This style of construction necessitated the use of a high frame and of a complication of parts, which, under some circumstances, are undesirable; and one of the main purposes of this invention is to so construct 80 and arrange the operative parts of a mining-machine that it shall occupy but a short diameter or dimension vertically. Another object is to relieve the sliding carriage of the weight of the engine or engines and the weight 85 of the parts to which the engines first impart motion.

In the drawings, *A A'* represent the side sills of a stationary bed-frame, and *A²* cross pieces or braces. Upon the inner side of the side-pieces, *A A'*, "ways" are formed to support and guide a sliding frame. These ways 95 may be of any of the species shown in my aforesaid patents, or of any approved character.

B B' represent engine-cylinders constructed 100

to operate by means of compressed air, or steam, or other motive agent. They are situated upon substantially horizontal lines, and are secured to the stationary frame-work. They 5 may be attached in any preferred manner.

C is the main shaft of the engine, supported above the rear end of the frame. It is mounted in bracket-arms C' C², bolted to the rear end of the frame, as shown in Fig. 8.

10 The pistons B² B² may be connected with the engine-shaft C in any suitable manner.

In the construction shown in the drawings, b b are slotted arms or yokes, engaging with the crank-pins c in a well-known manner. Instead of this construction, use may be made, 15 if desired, of pitmen or of oscillating engines.

A frame is arranged to slide upon the stationary frame above described, the sliding frame being supported on the stationary frame 20 by means of tongue-bars or T-bars D. The sliding frame is represented as being formed of a substantially horizontal plate, E, an arched standard E', at the front end of the sliding frame, and an arched standard, E², at 25 the rear end of said frame. These parts may be formed in one piece of metal or in separate pieces bolted together. The plate E is secured to the T-bar D adjustably, by means of bolts and nuts at e e, inserted through slots e'.

30 F is standard or upright, secured to the stationary frame A A' at its rear end.

The sliding frame above described is moved forward by means of a screw-threaded shaft, G, which is supported in the standard F, at 35 the rear end of the stationary frame, and in a corresponding standard, A⁴, at the front end of the stationary frame, as fully set forth in my previous patents.

H is a bevel-wheel, keyed to the screw-shaft

40 G, which latter extends to the rear of the standard F sufficiently far to support it.

I is a small bevel-wheel, mounted on and rotated by the shaft C. It engages with the wheel H, and through these devices the power 45 is transmitted to the screw-shaft G.

K represents the nut-holder, and indicates the position of the nut, which is caused to engage with the screw-shaft when the sliding frame is to be thrust forward toward the coal.

50 The construction in detail of this nut-holder and nut need not here be described, as they are fully shown and described in my previous patents, I preferring to use that shown in Patent No. 232,280, September 14, 1880. When

55 the nut is engaged with the shaft, the forward cylindrical part, k, of the nut-holder bears against the front standard, E', of the stationary frame. The nut can be disengaged from the shaft by sliding it on the same in the manner set forth in the last aforesaid patent.

60 With my present construction I not only carry the cutting apparatus forward by means of the screw-threaded shaft, but I also impart the required motion to said apparatus from this same shaft.

65 L represents the cutter-bar, which also may

be of any of the characters I have heretofore shown and patented; and L' L' are the chains for rotating said bar. The chains receive motion from a shaft, M, mounted on the plate E 70 of the sliding frame. M' is a miter-pinion attached to the shaft M.

N is a short supplemental shaft, mounted in said plate E, on a line situated in the same vertical plane as the screw-shaft G, and in the same 75 horizontal plane as the rear chain-shaft, M.

N' is a bevel-wheel, mounted at the front end of the short shaft N, and engaging with the miter-wheel M'.

Power is applied to the shaft N by means of 80 a spur-wheel, O, keyed to the rear end of said shaft, and a spur-wheel, P, mounted on the screw-shaft G. The shaft G engages with the wheel P by means of a feather or spline on the wheel fitted within a slot running parallel to 85 the axis of the screw. Thus the wheel, while rotating with the screw, is at the same time permitted to traverse the screw longitudinally, and as the cutter-carriage is moved forward, said wheel is moved along the shaft by means 90 of the rear standard, E², which, as will be seen by an examination of the drawings, is so situated as to bear against the rear face of the wheel.

p is a boss projecting from the face of the 95 wheel and arranged to provide a mounting for it within the standard E². p' is also a boss projecting from the opposite side or face of the wheel.

It will now be seen that if power be applied 100 to shaft C in the direction of the arrow 1 in Fig. 2, the screw-shaft will be rotated, and, as a result, the wheels P, O, N', and M' will be rotated in such direction as to rotate the cutter properly for cutting the coal, and if the 105 nut at K be held in engagement with the screw the cutter-carriage will be at the same time moved forward; but as it is desirable to move the machine forward with a speed different from that which it would obtain in the manner last described I interpose between the nut and the power devices the following mechanism:

Q is a spur-wheel keyed to shaft N, and Q' 110 is a spur-wheel of diameter equal thereto and keyed to the cylindrical portion k' of the nut-holder. By an examination of the drawings it will be seen that the wheels Q Q' differ in diameter from the wheels O and P to such an extent that while the wheel O is rotating the 115 cutters, the wheel Q is rotating the nut-holder K in the same direction as the screw-shaft G is rotating, and that the result of the rotations of the shaft and of the nut is to move the nut forward with a speed lower than it would have 120 if operated directly by the screw-shaft G. The nut-holder can readily rotate around the screw-shaft, owing to the smooth cylindrical inner surface of the holder k k'.

In order to prevent wear of the parts to as 130 great a degree as possible, washers g g' may be employed at the points where the screw-

shaft bears backward against the stationary standard F, and where the nut bears against the sliding standard E. The rear end of the nut-carrier k k' surrounds the boss p' on wheel 5 P, which provides a bearing for it.

By means of the slotted plate E and the adjusting-bolts at e e the chains L' L' may be adjusted so as to keep them always properly tight.

10 By mounting the engine in the manner which I have described and applying power directly therefrom to the screw-threaded shaft, and by arranging the parts so that said shaft shall not only move the carriage forward, but shall 15 also rotate the cutters, I am enabled to provide a much simpler construction than heretofore, and to place the parts of the machine more compactly than can be done when several chains are necessary for imparting the 20 power to produce the various required motions.

In many mines the material to be operated upon is so hard that it is almost impossible to cut it with steel, and I have devised a peculiar construction of cutter-bar and cutters 25 for the purpose of producing a kerf.

My improved cutter-bar is represented by L, and is shown to be mounted and rotated substantially as heretofore.

l represents a helical projection around the 30 bar. The outer face of the helical projection l is armed with diamonds l'. These diamonds are so placed that when revolving each vertical plane throughout the whole face or space of the kerf shall be covered or traversed by one 35 or more of the diamonds.

I am aware that diamonds have been used upon the ends of drills, both reciprocating and revolving; but when thus arranged they are not available for my purpose. It will be seen 40 that I arrange them between the ends of the revolving support in such positions that they shall rotate in planes transverse to the axis of said revolving support. This arrangement enables me to cut a long kerf by thrusting forward the bar which supports the diamond. 45

The cutter-bar may be of any desired length and diameter, and the projection of the diamonds from the bar may be varied as circumstances require. I prefer a projection of about 50 three-fourths of an inch. The "pitch" of the coil or helix may also be greater or less than that shown.

In order to remove the material lying in the path of the chains and the sprockets L² of the 55 cutter-shaft, said sprockets may be provided with diamonds l' for cutting away the material in said path, or they may have cutters attached like those in my former patents. The diamonds may, if preferred, be arranged in lines 60 parallel with the axis of the cutter, or without regularity relatively to each other.

To withdraw the cutting mechanism from the coal after the operation of cutting has been completed, use may be made of any of the devices shown in my aforesaid patents; but in 65 the drawings I have shown two devices or

mechanisms for this purpose, especially adapted to machines whose parts are constructed and arranged as above set forth.

D' represents a screw-threaded shaft mounted 70 on the stationary frame of the machine parallel to the shaft G, the two shafts having their axes in the same horizontal plane.

D² is a spur-wheel attached to the shaft D' at any suitable point, and meshing with a wheel, 75 G', on the screw-threaded shaft G.

F' F² represent, respectively, the upper and the lower parts of a nut carried by the movable frame, and arranged to be engaged with or disengaged from the shaft D', at the will of 80 the operator. When the cutter-frame is moving forward the nut F' F² is disengaged from shaft E', the nut K being at that time in engagement with the shaft G. When the cutter-frame is to be withdrawn the nut K is disengaged from shaft G, and the nut F' F² is thrown into engagement with the shaft D'. 85 The thread upon shaft D' runs in the same direction as the thread upon shaft G; but as the shaft D' rotates in a direction opposite to that of shaft G, it will be seen that the cutter-frame will be withdrawn, although the shaft G revolves continuously in one direction. The nut F' F² may be attached to the frame at any desirable point, though I prefer to join 90 it thereto by means of the standard E² at the rear end of the frame, said standard being formed of a peculiar shape adapted to support the nut, the supporting device being distinctly shown in Fig. 4.

E³ is an upright attached to or formed with the standard E². It is provided with a dovetailed groove, e², upon its outer face. The parts F' F² of the detachable nut carry dovetailed tongues or plates f f', which are fitted 105 within the groove e².

E⁴ is a stud-shaft projecting outwardly from standard E³.

E⁵ and E⁶ represent cams or eccentrics rigidly secured to the stud-shaft E⁴, and situated 110 diametrically opposite to each other.

E⁷ is a handle attached to the eccentrics E⁵ and E⁶, and by means thereof said eccentrics may be simultaneously rotated around the stud-shaft E⁴.

E⁸ is a strap around the eccentric E⁵, and pivoted to the dovetailed plate f.

E⁹ is a stirrup or yoke pivoted at its lower end to the dovetailed plate f', and at its upper end formed with a strap, F⁵, which fits the 120 eccentric E⁶.

By examining Figs. 4 and 5 it will be seen that, by means of the devices just described, the nut F' F² may be at any instant disengaged from shaft D', or engaged therewith, by 125 simply turning the handle E⁷.

In Fig. 7 I have shown a device for withdrawing the cutting mechanism in many respects similar to those shown in my previous patents above mentioned. In said figure R represents a shaft mounted above the rear standard, F. R' is a spool or reel keyed to the 130

shaft R, and R² is a sliding pinion supported loosely upon the same shaft. The pinion carries a conical hub, r, which can be caused to engage with the flaring or conical recess formed in the end of the spool R' in a manner substantially similar to that shown in Patent No. 232,280, September 14, 1880. The pinion may be shifted upon the shaft R by a lever engaging at r' with the sleeve, which carries the pinion R².

10 Power may be carried from the engine-shaft C to the pinion R² by a spur-wheel, S, on said shaft and idler-wheels S' S².

U represents a rope or chain, which at one end is attached to the spool or reel R, and at the other end is secured to the sliding carriage by means of an eye, u. To withdraw the cutters by devices of this character the pinion R² is moved so as to cause the hub r to engage with spool R', (the nut at K being disengaged from shaft G,) whereupon the said spool is rotated with shaft R, the rope U is wound around the spool and the sliding frame is drawn back until it reaches the standard E.

In order to more clearly show the cleaner-chains and the devices which support and operate them, I have shown them, together with said devices, in a separate view in Fig. 6. They are, however, in practice attached to the construction shown in Fig. 1, as will be readily understood, there being no modification whatever required of such construction to receive the chains.

Referring particularly to Fig. 6, O' represents a shaft mounted on the sliding-carriage on a line parallel to the cutter-bar and between said bar and the front standard, A⁴, of the stationary frame. At the outer ends of these shafts there are sprockets o.

O² O² are short shafts mounted in yokes or 40 stirrups O³ O³. These yokes or stirrups are supported by the brackets P' P', bolted at their inner ends to the sliding carriage of the machine, as shown at p². The brackets P' extend outwardly over the top of the stationary sills

45 A A'. The yokes or stirrups O³ are attached to the overhanging brackets P' by means of screw-threaded stems or shanks O⁴, which pass through apertures in the brackets made for their reception. The position of each yoke or 50 stirrup can be readily adjusted by means of the nuts O⁵, and in this way the tension of the chain can be regulated. The short shafts O² are provided with sprockets o'. The cleaner chains Q' are mounted upon the shafts O' and O², and are arranged to engage with the sprockets o and o'. Q² Q² are loops of metal attached to the sides of the chain at suitable intervals. They are formed with feet or lugs q, through which pass the pivots or connecting- 60 pins of the chains Q'. These loops Q² serve to gather and withdraw the "slack" or cuttings made by the cutters, and to carry them away from the kerf.

I prefer to operate the cleaner-chains by means of a chain, K², rotated by the spur-wheel M² on the shaft M. The chain K² engages with a sprocket-wheel, K', on the shaft O'.

Octagonal sprocket-wheels, such as shown in Fig. 9, may be employed upon the rear chain-shaft instead of the square or four-sided sprocket-wheels shown in the other figures, though either may be employed, as desired.

Many of the devices shown and described in this patent are also found in another case, the application for which was filed October 5, 1880, and patented of even date herewith. Hence, I do not claim herein anything shown or described in the said other case referred to.

What I claim is—

1. In a mining-machine, the combination of 80 the following elements, viz: a stationary bed-frame, a sliding cutter-frame, a screw-threaded shaft arranged to advance the cutter-frame, and a second screw-threaded shaft parallel with the first-named shaft and connected therewith by gearing, and thereby to be rotated continuously when the cutter-shaft is being rotated, substantially as set forth.

2. In a mining-machine, the combination of 90 the following elements, viz: a stationary bed-frame, a sliding cutter-frame, a screw-threaded shaft arranged to advance the cutter-frame, and a second screw-threaded shaft arranged to withdraw the cutter-frame and to be operated by the other said screw-threaded shaft, substantially as set forth.

3. The combination, with a stationary frame, a sliding frame, and a rotating screw-threaded shaft mounted upon the stationary frame, of the detachable nut-sections F' F², the pivoted eccentrics E⁵ E⁶, and the straps F³ F⁵, respectively attached to the nut-sections F' F².

4. In a mining-machine, the combination, with a rotating bar, of diamonds arranged between the ends of said bar to rotate in planes transverse to the axis of the bar, substantially as set forth.

5. In a mining-machine, the combination, with rotating bar L, of the projection l, extending from the face of the bar, and the diamonds l', embedded within said projection between the ends of the bar, substantially as and for the purposes set forth.

6. The combination, with the sliding cutter-frame, of the overhanging brackets P', the yokes or stirrups O³, the sprocket-shafts O², and the chains Q', substantially as set forth.

7. The combination, with the cleaner-chains Q', of the loops Q² attached to the sides of said chains, substantially as set forth.

In testimony whereof I affix my signature in presence of two witnesses.

FRANCIS M. LECHNER.

Witnesses:
